CLAIM

The ornamental design for a bottle opener, as shown and described.

DESCRIPTION

FIG. 1 is a bottom, right perspective view of a bottle opener according to the present invention;

FIG. 2 is a front view of the bottle opener of FIG. 1;

FIG. 3 is a rear view of the bottle opener of FIG. 1;

FIG. 4 is a left side view of the bottle opener of FIG. 1;

FIG. 5 is a right side view of the bottle opener of FIG. 1;

FIG. 6 is a bottom view of the bottle opener of FIG. 1;

FIG. 7 is a top view of the bottle opener of FIG. 1; and,

FIG. 8 is a bottom view thereof, shown in an environment of use.

The broken lines shown in FIG. 8 illustrate environmental detail and form no part of the claimed design.
